UNITED STATES PATENT OFFICE.

HENRY C. PFAFF, OF NEWARK, NEW JERSEY, ASSIGNOR TO TRAFFIC AND STREET SIGN COMPANY, OF NEWARK, NEW JERSEY, A CORPORATION OF NEW JERSEY.

DESIGN FOR A SIGNAL STANDARD.

Application filed June 27, 1928. Serial No. 27,294. Term of patent 14 years.

To all whom it may concern:

Be it known that I, HENRY C. PFAFF, a citizen of the United States, residing in the city of Newark, county of Essex, and State of New Jersey, have invented a new, original, and ornamental Design for a Signal Standard, of which the following is a specification, reference being had to the accompanying drawing, forming a part thereof.

In the drawing,

Figure 1 represents a side elevational view

of a signal standard showing my new design.

Figure 2 represents an enlarged sectional view taken on line 2—2 of Figure 1.

Figure 3 represents an enlarged sectional view taken on line 3—3 of Figure 1.

Figure 4 represents an enlarged sectional view taken on line 4—4 of Figure 1.

I claim:

The ornamental design for a signal standard, as shown.

HENRY C. PFAFF.
